UNITED STATES PATENT OFFICE.

JOHN F. O'CONNOR OF CHICAGO, ILLINOIS, ASSIGNOR TO WILLIAM H. MINER, OF CHAZY, NEW YORK.

OPERATING MECHANISM FOR HAND-BRAKES.

1,257,919.

Specification of Letters Patent. Patented Feb. 26, 1918.

Application filed March 1, 1916. Serial No. 81,335.

To all whom it may concern:

Be it known that I, JOHN F. O'CONNOR, a citizen of the United States, residing at Chicago, in the county of Cook and State 5 of Illinois, have invented a certain new and useful Improvement in Operating Mechanism for Hand-Brakes, of which the following is a full, clear, concise, and exact description, reference being had to the accompanying drawings, forming a part of this 10 specification.

My invention relates to hand brakes for railway cars.

The object of my invention is to provide a 15 brake of simple construction and efficient operation.

In the drawings forming a part of this specification, Figure 1 is an end view of a portion of a railroad car showing an assembled brake embodying my invention in position thereon. Fig. 2 is an enlarged vertical section taken at line 2—2 of Fig. 1. Fig. 3 is a transverse section taken on line 3—3 of Fig. 2. Fig. 4 is a vertical section illustrating a detail taken on line 4—4 of Fig. 3. Fig. 5 illustrates a modification of one of the parts.

Referring to the drawings, the numeral 6 indicates the end of a railroad car, a portion 30 of which is shown in the drawings. The car illustrated is of a gondola type, though it will be obvious that my brake may be used with any type of car. The brake is shown at 7. The numeral 8 indicates a casing within which the brake mechanism is mounted, the same being closed at its outer end by the preferably integral plate 9, and at its inner end by the plate 10. The casing 8 is provided with means, preferably the 35 lugs 11, suitably perforated for the passage of the rivets 12 which engage the casing and the plate 10 to the adjacent portion 13 of the car. The plate 10 is apertured as at 14 to provide a bearing for the inner end of the shaft 15, the shaft being mounted at its outer end in the bearing 16 provided in the outer plate 9 of the casing. The shaft 15 bears a drum 17 which is in the form shown in the drawings provided 45 with a helical groove 18 to receive the brake chain 19 in the winding and unwinding of the drum. The chain is fastened to the drum by suitable means as the lugs 20 and rivet 21 passing therethrough and through one of

the links 22 of the chain. This is shown in 55 Fig. 2 of the drawings. The shaft 15 also bears a wheel 23 the hub of which is indicated at 24, and the periphery is indicated at 25, and comprises a preferably in-turned collar or rim flange 26 forming a ring upon 60 which the pawls of the mechanism are adapted to be engaged as hereinafter described. In preferable construction, a space 27 is provided between the inner plate 10 of the casing and the adjacent edge of the 65 wheel 23. In this space is mounted the inner end of the operating handle 28, the said operating handle being provided with the preferably integral spaced-apart lugs 29—29 having a groove or way 30 between them of 70 sufficient width to permit the passage therethrough of the collar 26 of the wheel 23. The operating handle 28 passes through a slot 31 provided in the periphery of the casing, the same terminating in preferable construction at the point indicated by the numeral 32 in Fig. 3 of the drawings to permit the engagement of the operating handle 75 thereagainst when it hangs in its normal vertical position as illustrated in Fig. 3. A 80 stop-member 33 is provided within the casing to engage the side 34 of the inner end of the operating handle to hold the same in its released position as hereinafter described. The casing 8 is also provided with a slot 85 35 through which passes the holding or locking pawl 36, the locking pawl having without the casing a handle 37 and within the casing a pair of spaced-apart lugs 38—38 having a groove or way 39 between 90 them to permit the passage therethrough of the collar 26 of the wheel 23. A stop-member 40 is provided on the inner face of the casing for engagement with the locking pawl in the manner hereinafter described. 95

To wind the brake chain 19 upon the drum sufficiently to operate the brake mechanism underneath the car, which is not shown or described herein but which is well understood in the art, the operator moves 100 the handle from its normal position, as illustrated in Fig. 3, in a clockwise direction to rotate the wheel 23 and the drum 17 in the same direction. The lugs 29—29 on the operating handle are so spaced that upon exerting the pull described upon the handle, the same are engaged by the collar 26 of the wheel 23, thus transmitting the motion of 105

the lever to the wheel. The collar rides between the lugs of the holding pawl 36 until the operator ceases to apply force upon the lever, and upon such cessation the operating handle 28 slides upon the collar to its normal position against the stop-member 33. Upon such release of the operating lever, the counter rotation of the wheel 26 is prevented by the locking pawl 36, which engages against the curved face 42 of the stop-member 40, and is so mounted that, under the influence of gravity, it will bring the lugs 38 of the locking pawl into biting engagement upon the collar 26, thus preventing its counter rotation and the unwinding of the brake chain. In setting the brakes, if one movement of the operating lever is insufficient to wind the chain to a sufficient degree of tautness, the operation may be repeated until the brakes are set.

When it is desired to release the brakes, the chain is permitted to unwind by the release of the holding pawl, which is effected through the movement of the handle 37 thereof in a direction away from the casing, the stop 40 serving as a fulcrum upon which the lugs 38 are forced out of biting engagement with the collar 26, permitting the collar to run idly between the same on the unwinding of the chain. Meanwhile, the operating handle is prevented from biting the collar by the stop lug 33, inasmuch as the flat face 34 thereof holds the lever in a vertical position, thus permitting the collar to run between the lugs 29, the upper of which slides on the inner surface of the collar without biting engagement. It will be observed that when the handle 28 is in a line radial to the wheel 23, the lugs 29—29 do not bite the collar 26, but upon movement of the handle to a line not substantially radial to the wheel, the lugs 29 engage the collar and serve to rotate the wheel.

In Fig. 5 is shown a modified form of collar in which both the inner and outer faces of the collar 43 are undulated as at 44 to form depressions as at 45 to permit the ready biting of the lugs 46—46 upon the operating handle 47 therein.

50 I claim:—

1. In a brake, the combination with a wheel rotatable about a horizontal axis and having a collar, of means for actuating said wheel including a hand lever recessed at its upper end to loosely fit over said collar, said lever being supported by and normally depending from said collar in a direction radial of the wheel, and a fixed stop to engage

said hand lever and position it in said normal depending direction.

60 2. In a brake, the combination with a wheel rotatable about a horizontal axis and having a collar, of a hand lever recessed to fit over said collar and supported by and normally depending from said collar in a direction radial of the wheel, and a locking pawl also recessed to loosely fit over said collar at a different point in its circumference.

70 3. In a brake, the combination with a casing adapted to be secured to a wall, of a chain winding wheel rotatably mounted within said casing, said wheel having a rim flange, an operating hand lever recessed to fit over said rim flange and normally depending vertically therefrom, said hand lever extending through a recess in the casing, a locking pawl also recessed to fit over said rim flange and extending through another recess in the casing, and fixed abutments on 80 said casing to position said hand lever and locking pawl.

75 4. In a brake, the combination with a casing adapted to be secured to a wall, of a chain winding wheel rotatably mounted within said casing, said wheel having a rim flange, an operating hand lever recessed to fit over said rim flange and normally depending vertically therefrom, said hand lever extending through a recess in the casing, 90 a locking pawl also recessed to fit over said rim flange and extending through another recess in the casing, and fixed abutments on said casing to position said hand lever and locking pawl, the abutment for 95 said locking pawl having a curved fulcrum face.

5. In a brake, the combination with a casing adapted to be secured to a wall, of a chain winding drum rotatably mounted within said casing about a horizontal axis, said drum having an annular collar, a hand lever recessed at its upper end to loosely fit over said collar when extended radially of the wheel, said lever being adapted to bite 105 the collar when moved to a non-radial position, a vertical stop on the interior of said casing for determining the normal position of said hand lever, a locking pawl recessed to fit over said collar, and a curved fulcrum abutment with which said locking pawl cooperates.

In witness that I claim the foregoing I have hereunto subscribed my name this 11th day of February, 1916.

JOHN F. O'CONNOR.
